(57) **CLAIM**

The ornamental design for an administration kit and associated components thereof, as shown and described.

DESCRIPTION

FIG. 1 is an overhead perspective view of an administration kit and associated components thereof according to our design;

FIG. 2 is an overhead perspective view thereof with associated components in the form of a prefabricated syringe and a replacement cap;

FIG. 3 is an overhead perspective view thereof with the prefabricated syringe in the replacement cap;

FIG. 4 is a perspective view of the prefabricated syringe in the replacement cap;

FIG. 5 is a perspective view of the prefabricated syringe;

FIG. 6 is a bottom perspective view of an associated component of the administration kit in the form of a plunger for the prefabricated syringe;

FIG. 7 is a top perspective view of the plunger;

FIG. 8 is a side view of the plunger;

FIG. 9 is a bottom plan view of the plunger; and,

FIG. 10 is a top view of the plunger.

Portions of the administration kit and associated components thereof not shown in the provided views form no part of the claimed design.

1 Claim, 7 Drawing Sheets
